UNITED STATES PATENT OFFICE.

CHARLES ALGERNON PARSONS AND ALFRED QUINTIN CARNEGIE, OF NEWCASTLE-UPON-TYNE, ENGLAND; SAID CARNEGIE ASSIGNOR TO SAID PARSONS.

GOVERNING OF FLUID-OPERATED MOTORS.

986,943.

Specification of Letters Patent. Patented Mar. 14, 1911.

Application filed January 11, 1910. Serial No. 537,573.

To all whom it may concern:

Be it known that we, CHARLES ALGERNON PARSONS and ALFRED QUINTIN CARNEGIE, subjects of the King of Great Britain and Ireland, residing at Heaton Works, Newcastle-upon-Tyne, in the county of Northumberland, England, have invented certain new and useful Improvements Relating to the Governing of Fluid-Operated Motors, of which the following is a specification.

This invention relates to improvements in the governing of fluid operated motors of the kind which are operable by fluid of more than one pressure.

15 In mixed pressure turbine plants either of the type in which the turbine normally runs on low pressure working fluid but is provided with means for changing to high pressure supply or of the type in which the turbine normally runs on high pressure working fluid but is provided with means for changing to a low pressure supply a considerable alteration of speed may occur in changing from high pressure supply to low 20 pressure supply or vice versa, this alteration being additional to the variations which occur on account of changes of load. For instance, a turbine normally driven by low pressure fluid may rotate say three per cent. 25 faster than when it is being driven by high pressure fluid; this may occur even with such governing gear in which a special device is provided to close the low pressure inlet valve independently of the action of the 30 governor when a predetermined reduction in the pressure of the low pressure supply is exceeded. Hitherto however no means have been produced for varying the load on the 35 governor to control the amount of alteration of speed which occurs in thus changing from one pressure to another, although it has been proposed to operate the high and low pressure valves simultaneously through 40 floating levers or the like from the movement of the governor under variations of speed consequent upon changes of load.

The object of the invention is to provide means for varying the load on the governor of a mixed pressure plant so as to correct 45 the alteration of speed which occurs in consequence of changing the source of supply.

The invention consists in a device for controlling or regulating the alterations of speed which may occur in mixed pressure 50 turbines consequent upon changing the

source of pressure supply, said device being adapted to vary the load on the governor.

The invention also consists in combining the above mentioned controlling device for speed variations consequent upon changing 60 the source of supply with a controlling device for speed alterations under load changes, both devices being adapted to operate on one governor.

The invention further consists in combining the above device for controlling speed alterations consequent upon changing the source of supply with such controlling means in which a device is provided to close the low pressure inlet valve independently 70 of the action of the governor when a predetermined reduction in the pressure of the low pressure supply is exceeded.

The invention further consists in the speed governing or controlling devices for mixed 75 pressure turbines hereinafter described.

Referring now to the accompanying drawings:—Figure 1 shows one way of carrying the invention into effect, in which a Bourdon tube is used to influence the governor. Fig. 2 is a modification of the arrangement shown in Fig. 1 in which the leverage of the Bourdon tube can be varied. Figs. 3 and 4 show other arrangements for carrying out the invention, the latter figure showing one 85 form of the device as applied to a mixed pressure turbine.

While the mixed pressure turbine is running on the low pressure steam or other fluid the high pressure element is running idly, 90 and there is no difference of pressure between the two ends of that element but as soon as the supply of low pressure fluid falls and the high pressure fluid comes into action, there is a difference of pressure, and we utilize this difference of pressure to make the speeds at both working pressures the same as one another. It will be seen that a difference in speed will occur as a difference of pressure must be established across the high pressure element, but this actual alteration from the normal speed is a momentary one only, that is, one lasting only while the changing over is actually taking place so that the turbine shall run at the same speed 100 with either pressure.

In carrying this invention into effect according to one construction in which a Bourdon tube, *a*, be used as is shown in Fig. 1 one end of it is fixed opposite to a steam 110

pipe, *b*, connected to the high pressure part, *t*, of the turbine or engine at or near the high pressure inlet and the other end is connected by suitable means—say a link, *c*—
 5 to a rod, *d*, passing through a stuffing box, *e*, in a steam tight casing, *f*, which incloses the Bourdon tube, *a*. This casing *f*, is connected with the turbine or engine at or in front of the low pressure inlet to the low pressure element. The points of connection are represented in Fig. 3 by the reference letters, 10 *s* and *u* respectively. The rod, *d*, passing through the stuffing box, *e*, is connected directly or through any suitable means to the 15 end of a lever *g*, which acts upon the governor *h*. This lever is provided with a hand regulating spring, *i*, in order to vary at will the loading of the governor *h*.
 In operation the difference of pressure 20 across the high pressure element when high pressure fluid is being admitted to it will cause the curvature of the tube, *a*, to change and consequently the lever, *g*, which acts upon the governor, *h*, will be moved so as 25 to shift the governor collar *j*. Where as shown a ball governor is used in which with reduced speed the balls approach each other and raise the governor collar to open the valve, the Bourdon tube *a*, will through the 30 operating lever *g*, press in an upward direction on the governor collar, *j*, and thus bring the balls of the governor together faster than they would come together under ordinary circumstances by the action of the 35 spring, *k*, thus causing the steam supply valve to be opened quicker than the governor by itself would effect. The result of this is that the duration and amplitude of the speed variation are both reduced.
 40 It will be understood that the connection from the Bourdon tube, *a*, to the operating lever, *g*, may be of any suitable kind and in the modification of the invention shown in Fig. 2 the rod *d*, or other element which 45 passes through the stuffing box *e*, from the end of the Bourdon tube *a*, is connected to one end of a lever *m* which is mounted on a fixed pivot *n*, at the other end. Between the extremities of this lever *m*, are several 50 holes, *o*, to any one of which one end of a link, *p* may be connected the other end of said link being connected at any one of a corresponding number of holes *q* formed in the end of the lever, *g*, which acts 55 on the governor, *h*. The object of this arrangement is to enable some regulation to be obtained between the force produced in the Bourdon tube, *a*, by a given difference of pressure and that required to influence 60 or correct the governor, *h*, to the desired amount. It is of course obvious that any other suitable device may be used which will give suitable regulation in the leverage between the Bourdon tube or its equivalent 65 and the governor. A hand regulating spring,

i, is also provided. Throttle valves may also be fitted in the pipe or pipes leading to the Bourdon tube or its equivalent and dash pot may also be fitted.

In carrying this invention into effect in another manner as shown in Fig. 3 we provide in a cylinder, *w*, a piston, *x*, preferably gravity controlled and connected to one end of a lever, *y* which is pivoted at an intermediate point *z*, the other end of the lever, *y*, being connected by a link 70 *l*, or like device to a weight, *2*, which straddles over the end of a lever, *3*, pivoted at an intermediate point *4*, and connected directly or by suitable linkage to the free end of a pivoted 75 lever, *g*, which engages with the governor, *h*, this lever, *g*, being the same as that hereinbefore referred to. A hand regulating spring, *i*, as previously described, is also 80 provided. When the device is arranged for a mixed pressure turbine running normally on the low pressure, the bottom of the cylinder, *w*, is connected by a pipe, *13*, to the high pressure element at or near the high pressure inlet, and the top of the cylinder, *w*, is connected by a pipe, *14*, to the low pressure element at or in front of the low pressure admission point the two points of connection being represented in Fig. 4 by 85 the high pressure and low pressure inlet 90 valves, *s* and *u*, respectively as already mentioned. When the turbine is running on low pressure, the piston, *x*, is in its lowest position, and its connection with the weight, *2*, is of such a kind that the weight is lifted 95 free of the lever, *g*, this operation taking place by gravity, the weight of the piston *x* being greater than the weight, *2*. Under these circumstances the governor *h*, controls 100 the speed of the turbine in the ordinary manner, and takes care of changes of load. In changing over from low to high pressure supply, a difference of pressure is produced 105 between the two points of connection (*s* and *u*) of the cylinder, *w*, to the turbine, and the piston, *x*, is raised toward the top of the cylinder; this allows the weight, *2*, to sink upon the lever, *g*, and thereby loads the governor, *h*, but the connection between the piston lever, *y*, and the weight, *2*, is such 110 that the piston, *x*, may continue its up movement, after the weight, *2*, has become stationary. The effect of this is that the governor, *h*, is prevented from cutting off or 115 throttling the supply, until the speed of the turbine has become normal. By adjusting the load supplied to the governor *h*, by this weight *2*, any desired correction for the alteration of speed can be obtained for instance the lever, *y*, might be extended and 120 provided with a series of holes to which the link, *p*, could be attached, thereby adjusting the distance of the weight, *2*, from the fulcrum, *4*, of the lever, *3*.

A further modification is shown in Fig. 4 125 130

as applied to a mixed pressure turbine to which the high pressure steam is admitted by the valve, 5, and low pressure steam by the valve, *u*. The piston, *x*, within the cylinder, *w*, is arranged to act upon the governor lever, *g*, by a link, 7, to which the piston, *x*, is connected by a spring, 6, which is always under slight compression to insure that the piston, *x*, shall return to the bottom 10 of the cylinder, *w*, when no difference of pressure exists. The normal position of the piston, *x*, when the turbine is running on low pressure, is at the bottom of the cylinder, in which case the governor *h*, is free 15 to operate in its usual manner, but when changing from low to high pressure, the difference of pressure produced raises the piston, *x*, which thereby acts upon the governor *h*, in such a way as to load it, no 20 weight being employed. In order to insure the correct pressure being applied to the governor lever the piston, *x*, is made relatively large and its motion is limited by means of suitable stops. The size of the 25 piston is such that a very small pressure difference say one or two pounds per square inch is sufficient to raise it to the top of its stroke and so enable it to apply a definite and prearranged correction to the governor. It will be understood of course that 30 the speed correction when changing over from one source of supply to the other is a fixed amount and is independent of change of load and the same correction is required at 35 no load as at full load. The governor-lever, *g*, is pivoted at one end at 8 and has attached to its other end a piston, 9, working within a dash-pot 10. A spring 11, is also provided and arranged as shown, this spring being 40 capable of regulation by the hand wheel, 12. This spring, 11 is equivalent to the hand controlled spring, *i*, previously described.

The governor, *h*, controlling the speed of the turbine is geared to the turbine shaft, 45 18, by a belt, 19, running on pulleys, 20 and 21, the latter of which drives a governor shaft by means of bevel wheels, 16 and 17. Any convenient means may be employed for 50 connecting the operating element with the governor, for instance, levers, links, chains, pulleys and the like may be used. Also throttle valves may be fitted in the connections leading to the cylinder, *w*, etc., and dash pots may be fitted. The invention may 55 also be applied to governors other than of the centrifugal type, for instance, to fluid governors.

In cases where the mixed pressure turbine is run normally on high pressure steam, the 60 device may be suitably inverted in a manner which will be evident so that the governor shall be loaded in the opposite manner to that previously described.

Any of these devices for taking care of the 65 alterations of speed, consequent upon chang-

ing the source of pressure may be used in conjunction with any device for taking care of variations of speed, consequent upon changes of load, and if desired, in combination also with such controlling means in 70 which a device is provided for closing the low pressure inlet valve independently of the action of the governor when a predetermined reduction in the pressure of the low pressure supply is exceeded. 75

Having now fully described and ascertained our said invention and in what manner the same is to be performed, we declare that what we claim is:

1. In combination in a fluid operated 80 plant having a motor, a plurality of sources supplying working fluid to said motor at various pressures, a speed controlling device operable on a pressure difference in the interior of said motor between the admission 85 points thereto being established or removed.

2. In combination in a fluid operated plant having a motor, a plurality of sources supplying working fluid to said motor at various pressures, means governing the 90 speed of said motor, a speed controlling device operable on a pressure difference in the interior of said motor between the admission points thereto being established or removed, whereby on changing the source of fluid supply to the motor, said device influences said governing means to control any variation in 95 the speed of the motor.

3. In combination in a fluid operated 100 plant having a motor, a plurality of sources supplying working fluid to said motor at various pressures, means governing the speed of said motor under a variation of load and means controlling said governing means, 105 the operation of said controlling means being consequent upon changing the source of fluid supply to said motor.

4. In combination in a fluid operated 110 plant having a motor, a plurality of sources supplying fluid to said motor at various pressures, means governing the speed of the motor, means acting upon said governing means to restrain the movements thereof and means acting upon the governing means in opposition to said restraining means to control any change of speed consequent upon changing the source of fluid supply to said motor. 115

5. In combination in a fluid operated 120 plant having a motor, a low pressure and a high pressure source supplying working fluid to said motor and speed controlling means subjected to the pressure of the fluid in the high pressure source and to the pressure of that in the low pressure source whereby on changing the source of fluid supply to said motor, said means control any change in the speed of the motor. 125

6. In combination in a fluid operated 130 plant having a motor, a high pressure and a

low pressure source supplying working fluid to said motor, means governing the speed of said motor under a variation of load, an element adapted to be subjected to the pressure of the fluid in the high pressure and low pressure fluid sources and connected to said governing means, whereby said element influences said speed governing means to control any change of speed when the source supplying fluid to said motor is changed.

7. In a fluid operated plant having a motor, a high pressure and a low pressure source supplying working fluid to said motor, a rotary governor regulating the speed of said motor, a sleeve on said governor and a controlling device connected to said governor sleeve and operable on a pressure difference between the admission points to said motor being established or removed, thereby controlling the speed of said motor on the source of fluid supply thereto being changed.

8. In a fluid operated plant having a motor, a high pressure and a low pressure source of working fluid for said motor, a rotary governor regulating the speed of said motor and hand operated means to restrain the movement of said governor occasioned by a change of load on the motor, a device comprising a cylinder and a piston moving therein, said piston being subjected on one side to the high pressure fluid on the latter being supplied to the motor while the other side is always subjected to the low pressure fluid, suitable connections between said piston and governor, whereby on the source supplying the working fluid to said motor being changed, said device acts upon the governor to control any change in the speed of the motor.

9. In combination in a fluid operated plant having a motor, a high pressure and a low pressure source supplying working fluid to said motor, rotary governing means regulating the speed of said motor under a variation of load, an element subjected to the pressure of said fluid sources, lever means connecting said element with the governing means, and hand operated spring means connected to said lever means for varying the load on the governing means, whereby on the source supplying working fluid to said motor being changed said element acts upon the governing means to control any change in the speed of the motor.

10. In combination in a fluid operated plant having a motor, a high pressure and a low pressure source supplying working fluid to said motor, governing means regulating the speed of said motor under a variation of load, a cylinder, a piston movable in said cylinder and adapted to be subjected to the fluid pressure of both sources, lever means connecting said element with the governing means, and hand operated spring

means connected to said lever means for varying the load on the governing means, whereby on the source supplying working fluid to said motor being changed, said piston acts upon the governing means to control any change in the speed of the motor.

11. In combination in a fluid operated plant having a motor, a high pressure and a low pressure source supplying working fluid to said motor, rotary governing means regulating the speed of said motor under a variation of load, an element which can be subjected to the pressure of both of said sources, lever means connecting said element and governing means, hand operated spring means connected to said lever means for varying the load on said governing means, means for weighting said lever means, said weighting means being connected to said element and removable by the movements of the latter whereby on changing the source of supply to said motor, said element causes the weighting means to load the governing means and thus to control any change in the speed of the motor.

12. In combination with a turbine having a high pressure and a low pressure part, two sources of fluid at different pressures supplying working fluid to said parts and a speed controlling device subjected to the pressure of the fluid at the inlet point to each of said parts and operable on a difference of pressure between said inlet points being established or removed.

13. In combination with a turbine having a high pressure and a low pressure part, means governing the speed of said turbine and an element connected to said governing means and subjected to the difference of pressure across the high pressure part of the turbine, whereby on said high pressure part being connected with the low pressure part said element acts upon the governing means to control any change in the speed of the turbine.

14. In combination with a turbine having a high pressure and a low pressure part, means for governing the speed of said turbine under a variation of load, an element subjected to the difference of pressure established across said high pressure turbine part when the latter is supplied with working fluid, lever means connecting said governing means with said element and hand operated means connected to said lever means and adapted to vary the load on said governing means, whereby on said high pressure turbine being supplied with working fluid said element acts upon said governing means to control any change in the speed of the turbine.

15. In a fluid operated plant having a motor, a source of high pressure and a source of low pressure working fluid, means controlling the variation in the speed of said

motor consequent upon changing the source of fluid supply and means acting independently of any speed governing means to shut off the low pressure source when a predetermined reduction of pressure in the low pressure source is exceeded.

16. In combination with a turbine having a high pressure and a low pressure part, means for governing the speed of said turbine under a variation of load, a cylinder and a piston moving therein, said piston being subjected on one side to the pressure of the fluid in the high pressure turbine part and on the other side to the fluid pressure 10 in the low pressure turbine part, lever means 15 connecting said piston with the governor

means and hand adjustable means acting to load the governing means and also connected to said lever means, whereby on one of said turbine parts being put out of action, said piston moves within the cylinder and controls the amount of load put on the governing means by the loading means thus preventing a sudden change in the speed of the motor. 20
